SHEET FEEDER AND POSITIONER FOR
TYPEWRITERSLouis F. Hageman, Niagara Falls, N. Y., assignor
to American Sales Book Company, Inc., Niagara
Falls, N. Y., a corporation of Delaware

Application April 10, 1939, Serial No. 267,049

10 Claims. (Cl. 197—130)

This invention relates to improvements in writing machines such as typewriters, recording machines, tabulating machines, and the like, and more particularly to improved means for supporting and feeding, into writing position in the machine, record units such as single record sheets or unitary assemblages of record sheets and transfer sheets.

It is a general object of the invention to provide an improved supporting magazine with an improved feed initiating device for machines of the class mentioned which is well adapted for supporting a supply or stack of record units and automatically feeding them one after another into writing position on the machine platen.

A further object of the invention is to provide an improved supply magazine and feed initiating device of the class mentioned which can be readily attached to standard writing machines of the class mentioned without material alteration thereof and without interference with the machine operating mechanism.

Still another object of the invention is to provide for machines of the class mentioned a record supply supporting magazine having an improved feed initiating mechanism adapted to be connected for actuation to the operating mechanism of the machine so as to initiate feeding movement of the record units or assemblies from the magazine sequentially one after another into writing position on the machine platen.

A further object of the invention is to provide a supply magazine for machines of the class mentioned having an improved frictional device for supporting and controlling the movements of the record units.

A further object is to provide for machines of the class mentioned an improved supporting mechanism for a supply of record units which will effectively support the units in position for feeding them one after another into position on the machine platen which can be easily loaded with the record supplies, and moreover, is adapted for installation with very little trouble and with no material alterations of various standard writing machines.

Other objects of the invention will be in part pointed out in the following detailed description of an illustrative but preferred embodiment of the invention and will be in part obvious in connection therewith.

The invention accordingly comprises the features of construction, combination of elements, and arrangement of parts, which will be exemplified in the construction hereinafter set forth and

the scope of the application of which will be indicated in the claims.

For a more complete disclosure of the nature and objects of the invention reference is had to the following detailed description of the illustrative preferred embodiment, and to the accompanying drawings in which:

Fig. 1 is a perspective view of a typewriting machine of generally known construction and having the invention applied thereto;

Fig. 2 is a fragmentary plan view of the feed initiating mechanism parts being broken away and in section;

Fig. 3 is an enlarged vertical longitudinal section of the machine shown in Fig. 1, illustrating the supply magazine and feed initiating mechanism, parts of the machine being omitted and parts being shown in elevation;

Fig. 4 is a detail perspective view of one of the rear supporting brackets for the supply stack of record units; and

Fig. 5 is a detail transverse vertical section through the magazine showing one of the frictional control elements for the record units of the supply stack.

Referring to the drawings for a detailed description of the embodiment of the invention there shown, a typewriting machine 10 of generally known construction is fitted with the improvements. While the invention may be applied to writing machines of different standard types such as billing machines, tabulators, and the like, it is shown as being applied to a typewriter of standard construction. This typewriter is provided with a standard rotary platen 11 mounted

on a carriage 12 which may be constructed and arranged in well-known manner for effecting letter spacing and upper and lower case shift movements. Operating keys 13 are arranged in the form of a keyboard in the usual manner and are connected for actuation of type bars 14.

Pressure rolls 15 are mounted to press the record sheets or units into close contact with the periphery of the platen 11. These pressure rolls may be mounted in the usual manner upon a supporting arm 16 pivoted at 17 and arranged for

operation by a manually controlled member 18. The platen may be rotated for feeding the record paper by means of knobs or hand wheels 19. Other details of construction of the typewriting machine may conform to standard practice.

At the rear of the platen 11 is the record supply magazine 20 which is constructed and arranged for supporting a supply of record sheets or record units A arranged in a stack 21 in the

magazine. While these record sheets or units may vary specifically, the present improvements are adapted for utilizing manifolding sets or record units ordinarily embodying two or more record sheets with at least one interleaved carbon sheet all bound together into a unitary assemblage. Record units of this type are exemplified in the unitary manifolding assembly disclosed in the Stevens Patent No. 2,120,161, issued June 7, 1938. While the bound ends of the record units may be positioned at the rear or longitudinal side edges of the stack 21, it is preferable to position them at the forward end of the stack so that the bindings are at the advance ends of the units as they pass into writing position on the platen. As shown in the illustrative embodiment, the supply magazine 20 is mounted on the typewriting machine by means of laterally disposed supporting brackets 22 carrying transverse supporting rods 23 engaging downwardly turned flanges or brackets 24 on the bottom plates 25 of the magazine. These supporting flanges or brackets 24 are provided with openings for receiving the supporting rods. As shown, the magazine bottom 25 is provided with three bottom plate sections 25 which are slidable laterally along the supporting rods 23, and pivoted locking dogs 26 are mounted on the outer sections for engagement with one of the supporting rods 23 for the purpose of locking the bottom sections in adjusted position.

The supporting brackets 22 are detachably attached to structural supporting members or cantilever brackets 27 attached at their inner ends to the frame member 28 of the carriage 12. Since the frame member 28 moves laterally of the machine with the carriage 12 during letter spacing, the magazine 20 is mounted for similar movement. But the magazine 20 does not move vertically during vertical shifting movement of the carriage since the frame member 28 is separate from the vertical shifting part of the carriage. By means of this simple structure the magazine may be very readily attached to existing standard machines without any material alteration thereof.

As shown in Figs. 1 and 3 the bottom sections or plates 25 of the supply magazine are convexed upwardly along longitudinal lines, thus causing the supply stack 21 to assume a similar convexed position. At their rearward extremities these supporting sections 25 are inclined downwardly toward the rear while the forward parts are similarly downwardly and forwardly inclined adjacent to the rearward or sheet entry side of the platen 11. As seen in Fig. 3 this forwardly and downwardly inclined part of the convex supporting bottom 25 overlaps at the upper surface of the paper table or guide plate which is also forwardly and downwardly inclined and terminates at its lower forward edge close to the platen surface. Thus, the supporting bottom 25 and the paper table or guide plate provide a downwardly inclined continuous passageway through which the record units pass from the supply stack 21 to the platen. By means of this upwardly curved or convexed bottom the assembly or stack of record units is stabilized in its normal operative position in the magazine. A rearward terminal plate 29 is attached to the magazine in position 70 for supporting engagement with the rear end of the supply stack, preferably being bent as shown to form a pocket to receive the adjacent end of the stack. In order to accommodate record units of different lengths, this supporting plate 29 is 75 provided with a longitudinal slot 30 for receiving

attaching lugs 31, one or more of which is provided with a threaded nut whereby the supporting plate may be retained in adjusted position.

Each of the outer edges of the bottom sections 25 of the magazine is provided with an upwardly extending guide flange 32 preferably arranged at substantially right angles with the bottom plates 25 and forming retaining guides for the supply stack 21. These guide flanges may be adjusted to accommodate record units of different widths by sliding the sections 25 along the supporting rods 23. Each of the guide flanges 32 has an opening 33 for receiving frictional restraining elements 34 adapted to engage with the opposite longitudinal edges of the record units A of the supply pack 21. As best shown in Fig. 5, each friction restraining element 34 has a base 35 attached to a supporting plate 36 that has an attaching extension 37 provided with a resilient or yielding attaching clasp 38 adapted to slide on over the upper edge of the guide flange 32. When this attaching clasp 38 is thus engaged with the flange 32 as shown in Fig. 5, the frictional controlling element is supported in operative position within the opening 33.

While different forms of friction elements 34 can be used successfully, a particularly effective embodiment is disclosed which utilizes filamentary elements or bristles supported in substantially parallel relation with each other in a group or bunch in the base 35 in the manner of an ordinary bristle brush. The inner ends of these bristles extend into frictional contact with the adjacent longitudinal edges of the record units A so as to exert frictional restraint to advancement thereof and at the same time to retain the record units of the stack in correct assembled position in the magazine. The ends of the bristles will enter slightly between the record units for this purpose. The supporting shank 31 of the control element 34 is preferably of spring metal so as to yieldingly urge the bristles into controlling contact with the record units.

For the purpose of initiating movement of each individual record unit A from the supply stack 21 an improved feed starting mechanism is utilized. In the preferred embodiment this feed starting mechanism includes a swinging supporting frame indicated generally at 39 which has a swinging support arm 40 pivotally attached to the end portion of the platen shaft or spindle 41. For this purpose the attached end of the arm 40 has a supporting hub 42 through which the shaft 41 extends. If the original platen shaft is of insufficient length for making this attachment and for providing space for the auxiliary operating means, a short shaft extension may be applied at the adjacent end of the original platen shaft. A transverse supporting frame member 43 is attached to the arm 40 preferably being integral therewith and is provided at its outer or free end with a supporting extension 44 in which the adjacent outer end of the starter shaft or spindle 45 is journaled. At its opposite end the shaft 45 is journaled in a bearing in the outer end of the swinging arm 40.

Adjustably mounted upon the starter shaft 45 so as to be attached at different points therealong is the frictional starter element 46. The starter element 46 as shown is preferably in the form of a friction wheel or roller adapted to engage the adjacent upper surface of the record units in the supply stack. This starter wheel is ordinarily made of some substance affording frictional starting contact with the record unit sur-

face to provide the necessary starting effort. A suitable material for this purpose and one affording the requisite frictional contact effort is soft rubber, and sponge rubber is very well adapted 5 and preferred for this purpose.

Driving mechanism for the frictional starter wheel 46 includes a toothed gear wheel 47 meshing with a toothed idler 48 mounted for rotation upon a stub shaft or spindle 49 attached to the 10 swinging arm 40. The stub shaft 49 may be in the form of a cylinder appropriately attached at its inner end to the arm 40 and having a central bore for receiving an attaching screw 50 threaded at its inner end to the arm 40. The toothed idler 15 48 meshes in turn with the toothed pinion 51 secured to the adjacent end of the starter shaft 45. It will thus be seen that the frictional feed starting wheel 46 will be rotated through this 20 train of toothed gears when the platen 11 is rotated for effecting feeding movement of the record unit. The feed starting effort of the starter 46 will be in the same direction as the feeding effort exerted by the periphery of the platen. The toothed elements 47, 48 and 51 are preferably 25 made of fiberboard, thus reducing the weight, avoiding rattling.

A housing 52 is preferably provided for the toothed gears, being in the form of a finished metal plate and having an in-turned marginal 30 flange. It is attached in position by means of the binding screw 50 passing through an aperture in the plate. The platen shaft extension 41 also extends through an opening in the housing plate and forms a support for said housing.

35 The swinging starter frame 39 carries a guide plate 53 attached to the upper surface of the transverse frame member 43 and positioned for guiding engagement with the record sheet or unit as it passes from the upper surface of the platen. 40 An additional guide plate 54 is also attached to the swinging frame 39 and positioned for guiding engagement with the record unit to guide the latter in its movement from the supply stack into engagement with the receiving side of the platen. 45 As shown, the guide 54 may be constructed as an integral unit with the guide plate 53 and is ordinarily preferably made in the form of a light yielding metallic plate. The entire starter frame assembly is very light and yet sufficiently strong 50 to perform its functions effectively.

The supply stacks of record units may be very readily loaded into the magazine from above. Loading can be facilitated by swinging the starter frame 39 outwardly a short distance from its normal 55 operative position. When the stack is thus placed in position, the ends of the bristles of the friction brush will engage with the longitudinal edges of the record units, aiding in retaining the latter in position on the magazine, and offering light frictional restraint to movement of the record units.

60 Due to the upwardly convexed surface of the lower supporting plates 25 of the magazine, the opposite longitudinal ends of the record units will swing down or depend slightly from the middle portions thereof thus tending to retain them in their initial position in the magazine. When the starter frame is lowered, the starter wheel 46 will engage in frictional contact with the upper 65 surface of the upper record unit. Ordinarily the starter wheel will be maintained in its operative position by gravity but if desired a spring could be utilized for this purpose. Also, it will be noticed that rotation of the platen in forward feeding 70 direction tends to impart movement of the

starter wheel into frictional contact with the record units.

When it is desired to feed one of the record units A forwardly from the stack 21 into position on the platen, the platen is rotated thus 5 causing feed starting action of the friction starter 46. This action starts forward movement of the top record unit from the stack 21. When the forward edge reaches the grip between the platen 11 and the pressure rolls 15, the feeding action 10 of the unit is then effected by platen rotation supplemented by the starter 46. Typing of the record unit is then effected in the usual manner. When the typing is completed, the platen may be rotated to a sufficient extent to entirely free the 15 unit from the platen. During this feeding movement, the record units of the supply stack underneath the top unit will remain stationary in the magazine, being retained there by the action of the friction control elements 34 and by the convex 20 structure of the magazine bottom. Just as soon as the rear end of the typed record unit passes the friction starter 46 the latter comes into engagement with the next successive record unit to initiate its feeding movement toward the 25 platen. In this manner it will be seen that the record units will be fed sequentially one after another from the supply stack to and beyond the platen.

Instead of rotating the platen by means of the 30 hand wheel 19 after completion of the typing, the typed record unit can be freed from the platen by grasping its outer end and pulling it out so as to cause platen rotation. During such action the friction starter 46 is actuated to start 35 the next unit in the same manner as when the platen is rotated by means of the hand wheel 19. As shown it is preferable that the forward and rearward edges of the record units of the supply 40 stack 21 are progressively offset from each other or fanned, thus facilitating the starting and feeding action of the individual record units.

Since certain changes may be made in the above construction and different embodiments of the invention could be made without departing 45 from the scope thereof, it is intended that all matter contained in the above description or shown in the accompanying drawings shall be interpreted as illustrative and not in a limiting 50 sense.

Having described my invention, what I claim as new and desire to secure by Letters Patent is:

1. In a machine of the character described, in combination, a rotary platen, a magazine at one side of said platen for supporting a supply of record units, said magazine having an upwardly convexed supporting bottom which is downwardly inclined forwardly adjacent to the rear side of the platen and holding the supply in upwardly convexed position, means including a swingably mounted friction member operatively connected for simultaneous actuation with platen rotation for sequentially initiating feeding movement toward said platen of said record units one at a time, a unit guide mounted for swinging movement with said friction member for guiding the units to the platen from said friction member, and a friction device at said magazine in engagement with the edges of said record units at the upwardly convexed parts thereof to retain them in position in the magazine and to exert frictional restraint to advancement thereof. 65

2. In a machine of the character described, in combination, a rotary platen, a magazine adjacent to the platen for supporting a supply of rec-

ord units, said magazine having an upwardly convexed supporting bottom which is downwardly inclined forwardly adjacent to the rear of the platen where the forward end portion of the supply of record units is similarly downwardly inclined, a paper table downwardly inclined at the rear of said platen, said forwardly inclined part of said supporting bottom overlapping the similarly downwardly inclined paper table to form a downwardly inclined passageway to the platen, means operatively connected for simultaneous actuation with platen rotation for sequentially initiating movement of said record units one at a time toward said platen, said last mentioned means including a friction feed starting member engaging with the record units at the forwardly inclined end portion thereof and between the latter and the later mentioned friction device, and a friction device laterally adjacent to the convexed part of the bottom of said magazine in engagement with said record units to retain them in position in the magazine and to exert frictional restraint to advancement thereof.

25 3. In a machine of the character described, in combination, a rotary platen, a magazine adjacent to the platen for supporting a supply of record units, said magazine having an upwardly convexed supporting bottom which is downwardly inclined forwardly adjacent to the rear of the platen where the forward end portion of the supply of record units is similarly downwardly inclined, said bottom being downwardly inclined rearwardly at the rear of the magazine, a paper table downwardly and forwardly inclined at the rear of said platen, said forwardly inclined part of said supporting bottom overlapping the similarly downwardly inclined paper table to form a downwardly inclined passageway to the platen, means operatively connected for simultaneous actuation with platen rotation for sequentially initiating movement of said record units one at a time toward said platen, said last mentioned means including a friction feed starting member engageable with the record units adjacent to the downwardly inclined forward end portions thereof and between the latter and the later mentioned friction device, and a friction device laterally adjacent to the convexed part of said supporting bottom including a bunch of bristles having their end portions positioned for engagement with longitudinal edges of the record units to retain the latter in position in the magazine and to exert frictional restraint to advancement thereof.

55 4. In a machine of the character described, in combination, a rotary platen, a magazine adjacent to the platen for supporting a supply of record units, said magazine having an upwardly convexed supporting bottom upon which the supply rests in upwardly convexed condition and which is downwardly inclined forwardly adjacent to the rear of the platen and downwardly inclined rearwardly at the rear of the magazine, feed initiating means mounted for movement to and from the supply of record units and operatively connected for simultaneous actuation with platen rotation for sequentially initiating movement of said record units one at a time toward said platen, a unit guide mounted for movement with said feed initiating means for guiding the units to the platen and a longitudinally adjustable retainer at the rear of said magazine at the rearwardly inclined part of said bottom and having an inclined part for supporting the rear ends of the stack of record units in fanned condition.

5. In a machine of the character described, in combination, a rotary platen, a magazine adjacent to the platen for supporting a supply of record units, said magazine having an upwardly convexed supporting bottom upon which the supply rests in upwardly convexed condition and which is downwardly inclined at its rear part and downwardly inclined forwardly adjacent to the rear of the platen, feed initiating means operatively connected for simultaneous actuation with platen rotation for sequentially initiating movement of said record units one at a time toward said platen, a friction device laterally adjacent to the convexed part of the bottom of said magazine in engagement with said record units to retain them in position in the magazine and to exert frictional restraint to advancement thereof, said feed initiating means being positioned forwardly of said friction device at the downwardly inclined part of the supply of record units positioned on said downwardly inclined part of the supporting bottom, and a longitudinally adjustable retainer at the rear of said magazine at the rearwardly inclined part of said bottom for supporting the rear ends of the stack of record units. 25

6. In a machine of the character described, in combination, a rotary platen, a magazine adjacent to the platen for supporting a supply stack of record units, said magazine having an upwardly convexed supporting bottom upon which the supply rests in upwardly convexed condition and downwardly inclined forwardly adjacent to the rear of the platen, a friction member in frictional engagement with the upper record unit of the supply stack above the forwardly inclined part of the magazine bottom, driving means connected for simultaneous actuation of said platen and said friction member for initiating movement of said record units one at a time and feeding them over the platen, a swinging supporting frame for said friction member, and a guide carried by said swinging frame and positioned for guiding the record units. 30

7. In a machine of the character described, in combination, a rotary platen, a magazine adjacent to the platen for supporting a supply stack of record units, said magazine having an upwardly convexed supporting bottom downwardly inclined forwardly adjacent to the rear of the platen and downwardly inclined rearwardly at its rear end portion so as to support the supply stack in upwardly convexed condition with forward and rearward end portions downwardly inclined, a rotary friction member in frictional engagement with the upper record unit of the supply stack above the forwardly inclined part of the magazine bottom and at the forwardly and downwardly inclined end portion of the supply stack, driving means connected for simultaneous actuation of said platen and said rotary friction member for initiating movement of said record units one at a time and feeding them over the platen, and a friction device at said magazine rearwardly spaced from said rotary friction member and laterally adjacent to the convexed part of said supporting bottom intermediate the forwardly and rearwardly inclined end portions thereof for engagement with said record units to retain them in position in the magazine and to exert frictional restraint to advancement thereof. 40

8. In a machine of the character described, in combination, a rotary platen, a magazine adjacent to said platen for supporting a supply stack of record units, a rotary friction member in frictional engagement with the upper record unit of

- the stack in the magazine, driving means operatively connected for simultaneous actuation of said platen and said rotary friction member for initiating movement of said record units one at 5 a time, a swinging supporting frame for said rotary friction member positioned to the rear of said platen and pivotally mounted at the forward part thereof, and a guide plate attached to said swinging frame and positioned for guiding the 10 record units emerging from the platen.
9. In a machine of the character described, in combination, a rotary platen, a magazine adjacent to said platen for supporting a supply stack of record units, a rotary friction member in frictional engagement with the upper record unit of 15 the stack in the magazine, driving means operatively connected for simultaneous actuation of said platen and said rotary friction member for initiating movement of said record units one at 20 a time, a swinging supporting frame for said rotary friction member positioned to the rear of said platen and mounted at its forward part for

swinging movement, and guides carried by said swinging frame and positioned to guide the record units to and from said platen.

10. In a machine of the character described, in combination, a magazine for supporting a supply stack of record units, a friction unit including a bunch of bristles positioned for engagement in frictional relation with the edges of the record units, a guide plate opposed in guiding relation with the edges of the record units and having an opening for receiving said friction unit in operative position, and a yielding supporting attachment between said friction unit and an edge portion of said guide plate supporting said friction unit yieldingly in operative position in said 15 opening and including a supporting arm connected to the friction unit and having at its opposite extremity an attaching clasp forming a detachable attachment with said edge portion of said guide plate. 20

LOUIS F. HAGEMAN.
